UNITED STATES PATENT OFFICE.

JOSEPH REIF, OF HEBRON, INDIANA, ASSIGNOR OF FORTY-FIVE PER CENT. TO
FRANCIS E. LING, OF HEBRON, INDIANA.

BRAKE MECHANISM FOR RAILWAY-CARS.

1,391,977.

Specification of Letters Patent. Patented Sept. 27, 1921.

Application filed June 1, 1920. Serial No. 385,482.

To all whom it may concern:

Be it known that I, JOSEPH REIF, a citizen of the United States, residing at Hebron, in the county of Porter and State of Indiana, have invented certain new and useful Improvements in Brake Mechanism for Railway-Cars, of which I do declare the following to be a full, clear, and exact description, reference being had to the accompanying drawings, forming a part of this specification.

My present invention has for its object to provide improved brake mechanism whereby the wheel brakes will be automatically applied when the strain upon the draw heads in moving the car either in forward or backward direction is relieved.

The invention consists in the features of novelty hereinafter described, illustrated in the accompanying drawings and particularly pointed out in the claims at the end of this specification.

Figure 1 is a view partly in elevation and partly in longitudinal vertical section through a portion of a railway car having my invention applied thereto. Fig. 2 is an inverted plan view of the parts shown in Fig. 1. Fig. 3 is a view in vertical cross section on line 3—3 of Fig. 2. Fig. 4 is a view in vertical longitudinal section on line 4—4 of Fig. 3.

A designates conventionally the floor or under framing of a railway car to the bottom of which is secured a suitable transom B to which is pivotally connected the bolster C of the truck frame. The truck frame may be of any suitable construction but is shown in the drawings as comprising the upper truss member D and the lower bottom member E, these members carrying at their opposite ends suitable journal bearings for the journals of the car wheels F. Suitable brake beams G and G' are suspended from the bolster C by the links g and upon the ends of these brake beams are supported the brake shoes H and H' that engage with the wheels F to arrest their rotation. The construction of the parts above defined will be readily understood by those familiar with this class of devices and need not be more particularly described.

Through the forward brake beam G passes a bolt 10 the front end of which passes also loosely through the lower portion of a shifter bar 12, the front end of the bolt be-

ing provided with a nut 13. To the lower end of the shifter bar 12 is pivotally connected, as by a bolt 14, a link or coupling bar 15, the rear end of which is united as by a bolt 16 to the rear brake beam G'.

Through the upper portion of the shifter bar 12 passes a bolt 20 that is encircled by a coil spring 21. As shown, the rear end of the coil spring 21 bears against a nut 22 on the threaded rear end of the bolt 20, while the front end of the spring 21 bears against a bar 25 (that may be of spring metal) having a slot or hole therein through which the bolt 20 passes. The lower end of this bar 25 may be slotted or yoke-shaped to straddle the bolt 10 and the lower end of this bar 25 bears against the front face of the forward brake beam G. The spring 21 holds the upper end of the bar 25 against the upper portion of the shifter bar 12 and causes the rearwardly bowed lower portion of the bar 25 to bear with a yielding pressure against the front face of the brake beam G.

The front end of the bolt 20 that passes through the upper portion of the shifter bar 12 may be yoke-shaped and is pivotally connected, as at 27, to the rear end of a shifter link 28. Upon the forward portion of the bolt 20 is mounted an adjusting nut 29. The front end of the shifter link 28 is pivotally connected to a rock arm 30 that is pivotally mounted as at 31 between lugs 32 depending from the under side of the draw bar 33. Connected to or formed integral with this rock arm 30 is a similar rock arm 35, also pivotally mounted as at 31, so that the rock arms 30 and 35 move in unison. To the lower end of the rock arm 35 is pivoted as at 36 the rear end of a link or bar 37, the front end of which is pivoted as at 38 to a part depending from the end of the under frame of the car.

The draw bar 33 is chambered approximately from end to end (see Fig. 2) and is mounted to slide within a suitable frame 40 secured to the under frame of the car, the draw bar being shown as provided with laterally projecting arms or lugs 41 preferably formed integral therewith.

The forward end of the draw bar 33 is connected to the front end of a rod 45 (see Fig. 4) that extends thence through the rear end 46 of the draw bar and through the rear end 40^a of the frame 40. Upon the rear portion of the bolt 45 is mounted a sleeve 47

through which the bolt 45 is free to slide, the rear end of this sleeve bearing against the end 40^a of the frame 40. Upon the sleeve 47 is mounted a coil spring 50 the 5 rear end of which bears against the rear end 46 of the draw bar 33, while the forward end of the spring 50 bears against a plate or washer 51. In front of the plate or washer 51 and encircling the rod 45 is a coil spring 10 53 the rear end of which bears against the plate or washer 51, while its forward end bears against the adjusting nut 54 on the rod 45. The nut 54 is round and formed with peripheral holes to receive a bar or 15 spanner and by turning the nut 54 the tension of the spring 53 can be adjusted. The spring 53 tends to hold the draw bar 33 in the position shown in the drawings and by so doing to set the brakes upon the wheels. 20 When the draw bar is either pulled forwardly, or is pushed backwardly, this spring 53 is compressed, but as the forward or backward strain on the draw bar is released, the spring 53 brings the draw bar to the position 25 shown to set the brakes. The spring 50, (which is much lighter than the spring 53) serves to aid in moving backward the draw bar when this backward movement is to be manually effected by the crank handle 30. 69, as hereinafter described.

From the rear end of the frame 40 projects a lug 60 to which is pivotally connected, as at 61 (see Fig. 2) a lever 62. The inner end of this lever 62 (see Fig. 4) is perforated 35 or slotted where the rear end of the rod 45 passes loosely through it, the rear threaded end of the rod 45 being provided with a threaded nut or head 45^a. To the outer end of the lever 62 is pivotally connected as at 64 the rear end of a link 65, to the front end of which link is pivotally connected as at 66 a crank arm 67 that is formed or provided at the lower end of a vertical bar 68 (see Figs 2 and 3) having at its upper 40 end a crank handle 69 whereby it may be turned. This bar 68 is suitably mounted in a bracket 70 at the front end of the under frame of the car.

From the foregoing description, the operation 50 of my improved brake mechanism will, it is believed, be readily understood. When the draw bar 33 is in the position shown by full lines in the several views of the drawings, and no strain is being exerted 55 upon the draw bar either to move the car forward or backward, the brake shoes H and H' will be applied to the wheels F of the car and will check or arrest the rotation of the wheels. This pressure of the brake shoes 60 upon the wheels is due to the pressure of the springs 50 and 53 which serve to normally hold the parts in the position shown by full lines in the drawings, with the brake shoes set against the wheels. When, however, forward strain is exerted upon the

draw bar 33 to move the car in forward direction, the rock arms 30 and 35 will be shifted from the position shown by full lines in Fig. 4 to the position shown by dotted lines. This shift of the rock arms is 70 due to the fact that as the draw bar 33 is pulled forward, the link 37, in resisting the bodily forward movement of the rock arms causes these arms to turn about their center of movement 31. The lower end of the 75 rock arm 35 is thus swung upward, while the lower end of the rock arm 30 is swung rearwardly. This rearward movement of the rock arm 30 causes the shifter link 28 to push backward the upper end of the 80 shifter bar 12 and swing the lower end of this shifter bar 12 forwardly. This backward movement of the upper end of the shifter bar 12 causes the lower end of the bar 25 to move rearwardly the brake beam 85 G and thus move the brake shoes H from engagement with the front wheel F. The forward movement of the lower end of the shifter bar 12 will, through the medium of the connector bar 15, draw forwardly the 90 rear brake beam G', thereby causing the brake shoes H' to be released from the rear wheels F. Through the medium of the nut 22, the adjustment of the tension spring 21 can be regulated as desired and a corresponding regulation of the pressure that will be exerted by the bar 25 to release the brake beams G and G' can be effected.

It will be understood, however, that the pressure exerted by the spring 21 tending 100 to release the brake beams will be materially less than the pressure exerted by the springs 50 and 53 to set the brake shoes against the wheels when the strain upon the draw bar is relieved. When the draw bar 33 is moved backward, as in moving the car rearwardly, the connector link 28, in resisting the rearward movement of the lower end of the rock arm 35 will cause the rock arm to turn about 105 their center of movement 31 as they are forced backward and will cause the upper end of the shifter bar 12 to be moved rearwardly and its lower end to be moved forwardly, as hereinbefore described, so as to 110 relieve the pressure of the brake shoes H and H' against the front and rear wheels F. When the backward pressure upon the head of the draw bar is relieved, the springs 50 and 53 will restore the draw bar to normal 115 position and reset the brake shoes against the wheels.

Whenever it is desired to relieve the pressure of the brake shoes against the wheels so as to enable the car to be shifted at times 120 when it is not coupled to the locomotive, this can be effected by the attendant turning the crank handle 69 on the vertical rod 68. This turning of the crank handle 69 will cause the crank 67 at its lower end to swing 125 130

forwardly the link 65 and to rock the lever 62 about its pivot point 61, thereby causing the inner end of the lever 62 to draw rearwardly the rod 45 and the draw bar 33, and 5 as before stated, when the draw bar 33 is thus moved backward manually, the spring 50 will aid the operator in effecting such backward movement. This rearward movement of the draw bar 33 will serve to relieve 10 the pressure of the brake shoes H and H' upon the wheels F in manner hereinbefore described.

My invention affords an extremely simple and effective means for automatically setting and releasing the brake mechanism of 15 railway cars. A further advantage incident to my invention is that when a car or series of cars are disconnected from the locomotive and are at rest, the brakes will be 20 automatically set so that the danger of the car or cars moving accidentally when placed upon an inclined track is avoided.

Having thus described my invention, what I claim as new and desire to secure by Letters Patent is:—

1. In brake mechanism for railway cars, the combination of a brake beam and brake shoes, of a longitudinally movable draw bar, pressure mechanism tending to hold said 30 draw bar at a point intermediate the limits of its movement, connections between said draw bar and the brake beam whereby the brake shoes are applied to the wheels when the draw bar is at such point and whereby 35 the brake shoes are released when the draw bar is shifted, and means whereby said draw bar may be manually shifted.

2. In brake mechanism for railway cars, the combination of a brake beam and brake 40 shoes, of a longitudinally movable draw bar, pressure mechanism for holding said draw bar at a point intermediate the limits of its movement, a shifter bar connected with the 45 brake beam, rock arms pivotally connected to the draw bar, and means connecting said rock arm to said shifter bar.

3. In brake mechanism for railway cars, the combination of a brake beam and brake 50 shoes, of a longitudinally movable draw bar, springs acting in opposite directions for shifting said draw bar to a point intermediate the limits of its movement, and connections between said draw bar and the brake beam whereby the 55 brake shoes are applied to the wheels when the draw bar is at such point and whereby the brake shoes are released when the draw bar is shifted.

to the wheels when the draw bar is at such point and whereby the brake shoes are released when the draw bar is shifted from such point.

4. In brake mechanism for railway cars, the combination of a brake beam and brake 60 shoes, of a longitudinally movable draw bar, a pair of rock arms depending from said draw bar, links connected to said rock arms, and a shifter bar connected to the rear end of one of said links and connected to said 65 brake beam.

5. In brake mechanism for railway cars, the combination with a pair of brake beams and their brake shoes, of a longitudinally movable draw bar, pressure mechanism tending to hold said draw bar at a point intermediate the limits of its movement, and connections between said draw bar and said 70 brake beams whereby the brake shoes are applied to the wheels when the draw bar 75 is at such point and whereby the brake shoes of both brake beams are released when the draw bar is moved from such point.

6. In brake mechanism for railway cars, the combination with a brake beam and 80 brake shoes, of a longitudinally movable draw bar, a rod extending lengthwise of said draw bar, oppositely disposed springs mounted upon said rod tending to hold said draw bar at a point intermediate its limits 85 of movement, and connections between said draw bar and the brake beam whereby the brake shoes are applied to the wheels when the draw bar is at such point and are released from the wheels when the draw bar 90 is moved from such point.

7. In brake mechanism for railway cars, the combination with a brake beam and 95 brake shoes, of a longitudinally movable draw bar, a rod extending lengthwise of said draw bar, oppositely disposed springs mounted upon said rod tending to hold said draw bar at a point intermediate its limits of movement, connections between said draw bar and the brake beam whereby the 100 brake shoes are applied to the wheels when the draw bar is at such point and are released from the wheels when the draw bar is moved from such point, a lever engaging said rod, and means whereby said rod may be manually shifted to move the draw bar longitudinally. 105

JOSEPH REIF.
